UNITED STATES PATENT OFFICE.

ALBERT L. BABCOCK, OF BILLINGS, MONTANA.

DESIGN FOR A SHEPHERD'S CROOK.

SPECIFICATION forming part of Design No. 21,816, dated August 30, 1892.

Application filed July 26, 1892. Serial No. 441,337. Term of patent 14 years.

To all whom it may concern:

Be it known that I, ALBERT L. BABCOCK, of Billings, in the county of Yellowstone and State of Montana, have invented and produced a new and original Design for a Shepherd's Crook, of which the following is a specification, reference being had to the accompanying drawing, forming a part thereof, which represents a perspective view of a crook embodying the features of my design.

The design consists of straight lines 10, apparently losing themselves at one end in lines 11 and 12, curved jointly to approximate the shape of one side of an ellipse. The lines 15 12 connect with lines 13, and these latter lines are curved abruptly inward apparently op-

posite and quite near to the point of junction of the lines 10 and 11, and from that point they are curved in an opposite direction and with a full and decided sweep from the straight 20 lines. The shape of the space between the upper portions of the lines 13 and the lines 11 and 12 consequently approximates the shape of a pear.

I claim—

The design for a shepherd's crook, substantially as herein shown and described.

ALBERT L. BABCOCK.
